Attorney.

UNITED STATES PATENT OFFICE.

GOSHEN SWEYN RICHARDSON, OF SYDNEY, NEW SOUTH WALES, AUSTRALIA, AS-
SIGNOR TO NUPEG (AUSTRALIA) LIMITED, OF WATERLOO, SYDNEY, NEW SOUTH
WALES, AUSTRALIA, A CORPORATION OF NEW SOUTH WALES.

CLOTHES PEG.

Application filed April 6, 1925, Serial No. 21,086, and in Australia May 27, 1924.

This invention relates to wire pegs employed for securing clothes to clothes lines, and provides a simple, easily constructed, and durable wire peg that will reliably secure the clothes to the line and avoid the tearing of same.

The accompanying drawings illustrate the invention, and therein:

Figure 1 is an elevation of the peg,
10 Figure 2 is an elevation taken at a right angle to Figure 1, and

Figure 3 is a perspective view illustrating the peg in use on a clothes line.

The peg is formed by bending a wire between its ends into a nearly circular portion 1 which acts as a spring and then bending the end portions to extend transversely of said circular portion with their extremities 3 projecting just beyond the uppermost central part 4 of said circular portion to form a pair of gripping prongs 2. The extremities 3 of the prongs 2 are bent where they cross the circular portion to avoid tearing of the clothes.

25 The two prongs 2 which are practically straight, are at a distance from one another where they are bent from the circular portion, thus forming a mouth 5, and converge toward their extremities 3 to form a space 6 which becomes narrower from said mouth toward their free ends to ensure an increasingly tight grip as the peg is pressed down over the clothes on the clothes line 7.

It will be noted that the circular portion 1, where it merges into the prongs 2 is curved, thus forming a curved mouth which facilitates the application of the peg to the clothes and obviates damage to the clothes.

The circular portion is slightly dished as illustrated at 8 in Figure 2 and the extremities 3 of the prongs 2 are slightly bent as at 9 where they cross the part 4 of the circular portion.

Owing to the natural resiliency of the wire and the almost circular shape of the main portion of the peg, the prongs will

yield and spread apart when the peg is pressed down on the line and correspondingly will contract by reason of the spring action of the part 1 when the peg is removed from the line.

It will be noted that the somewhat semi-circular shaped gaps 10 between the prongs 2 and the arcuate parts of the portion 1 are each sufficiently wide to permit a finger to be inserted and so facilitate removal of the peg from the line.

I claim:

1. A clothes peg comprising a wire bent into substantially circular form and having its end portions bent to form prongs extending transversely of and beyond said circular portion, said prongs being spaced apart where they are bent from said circular portion and converging toward their free ends, 60 that part of the circular portion crossed by said prongs being bent out of the plane of its remaining portion, and said prongs adjacent at the points where they cross said circular portion being bent in the same direction as said bent part of said circular portion.

2. A clothes peg comprising a member bent between its ends into a substantially circular portion and having its end portions straight and curvilinearly bent from said circular portion so as to extend transversely of and beyond said circular portion, said straight portions where they are bent from said circular portions being spaced apart to 80 form a gap and converging toward their free ends, said circular portion being dished between the points at which said straight portions are bent therefrom and the points at which said straight portions cross the 85 same, and said straight portions being bent adjacent their ends beyond the plane of said dished portion.

In testimony whereof I have hereunto set my hand.

GOSHEN SWEYN RICHARDSON.
